Designer:

Franklin Field

United States Patent Office.

FRANKLIN FIELD, OF TROY, NEW YORK, ASSIGNOR TO HIMSELF AND CHARLES K.
AND CHARLES A. BROWN, OF SAME PLACE.

Design No. 3,495, dated May 11, 1869.

DESIGN FOR ORNAMENTING THE EDGES OF PAPER COLLARS.

The Schedule referred to in these Letters Patent and making part of the same.

To all whom it may concern:

Be it known that I, FRANKLIN FIELD, of the city of Troy, in the county of Rensselaer, and State of New York, have invented or produced a new and original Design to be stamped or embossed upon the edges or borders of collars, cuffs, or wristbands consisting wholly or in part of paper; and I do hereby declare that the following is a full and exact description of my said design, reference being had to the accompanying drawing, in which—

Figure 1 is a side view of a part of a paper collar, cuff, or wristband having my said design, and

Figure 2 is a cross-section of the same at the line *z z.*

Like parts are marked by the same letters in both figures.

This design consists of a broad, flat, raised surface,

A, with parallel edges, *b c*, along or upon the edge or border, and above the main portion D of the outer surface of the article, with longitudinal rows of indentations, *e e*, stamped therein, apart from each other, and along and near to the edges, *b c*, of the raised border A, as indicated by the aforesaid drawings, so as to make the article appear very much as if it were made of linen cloth, with a tape stitched along and upon its outer edge or border.

What I claim as my invention or production, is—
The design for the edges of paper collars, cuffs, or wristbands, as shown and described.

FRANKLIN FIELD.
